UNITED STATES PATENT OFFICE.

CHARLES W. EBELING, OF ELM GROVE, WEST VIRGINIA, ASSIGNOR OF ONE-HALF TO
HARRISON W. ROGERS, OF NEW YORK, N. Y., AND ONE-HALF TO GEORGE E. HOUSE,
OF WHEELING, WEST VIRGINIA.

DOMESTIC CHURN.

1,274,021.

Specification of Letters Patent.

Patented July 30, 1918.

Application filed March 9, 1918. Serial No. 221,440.

To all whom it may concern:

Be it known that I, CHARLES W. EBELING, a citizen of the United States, residing at Elm Grove, in the county of Ohio and State of 5 West Virginia, have invented certain new and useful Improvements in Domestic Churns, of which the following is a specification, reference being had therein to the accompanying drawing.

10 This invention relates to improvements in domestic churning, one object of the invention being the provision of a churn, the dasher member of which is bodily carried by a closure member, which is so constructed as to readily attach to a Mason jar, so that the 15 receptacle may be always at hand and the dasher member may be sold independently of the receptacle.

A further object of this invention is the 20 provision of a novel form of dasher mechanism which permits of the easy insertion or withdrawal of the dasher through the mouth of a jar and at the same time causes the rapid churning of the contents, the present churn being devised as a conservation measure in that a pound of butter to a pint of milk can be so churned as to produce two pounds of solid matter which can be used similarly to the butter.

25 A still further object of this invention is the provision of a device which is simple, durable and inexpensive in construction and thoroughly efficient and practical in use.

In the accompanying drawings:

30 Figure 1 is a small view showing the present device applied to a Mason jar.

Fig. 2 is a view partly in elevation and partly in section of the cap and closure member removed.

35 Fig. 3 is a plan view of the dasher member and its stem.

Fig. 4 is a plan view of the dasher member in open or spread position.

40 Figs. 5, 6 and 7, are detail views of the three dasher plates.

Referring to the drawings, the numeral 45 10 designates a Mason jar and 11 designates the cap or closure therefor, which is provided with a journaling tube 12 for the reception of the stem 13 which carries the operating handle 14 of the present device. The lower end of the stem 13 is provided with the reduced threaded portion 15 providing the shoulder 16 and a reduced cylind-

rical portion 17. Attached by means of 50 the nut 18 upon the threaded end 15 and held fixedly against the shoulder 16, is a blade or paddle 19, while mounted for free independent motion between the cylindrical portion 17, the lower paddle 19, and the upper paddle 21, is the intermediate paddle 20. These paddles, when in the position as shown in Figs. 3 and 4, constitute a perforated disk which when the present device is moved up and down form the churning of 55 the substance or material within the receptacle 10.

The upper section 21 is attached, by soldering or otherwise, to the sleeve 22, mounted for limited rotary movement upon the 60 lower end of the stem 13 and provided with the offset end 23 for coöperation with the offset 24 of the dasher or disk opening and closing tubular stem 25 carried by the cap 11. When it is desired to open or close the 65 blades 19, 20 and 21, the notched end of the stem 25 is placed in engagement with the notched end of the sleeve 22. By gripping the handle 24 and moving the stem 13, the sleeve 22 being held fixed by the stem 25, 70 and the blade 19 being fixed to the stem 13, this blade will move and cause its lug 28 to engage one edge of the blade 20 so as to move the blade 20 therewith, said blade 20 then having the opposite edge engage the 75 lug 30 of the blade 21 so as to move the blade 21 therewith, until the parts assume the position as shown in Fig. 4, or extended, the lug 32 of the blade 21 fitting in the recess 26 of the blade 19 and thus limiting the extension of the blades. In order to collapse the 80 blades it is simply necessary to rotate the stem 13 in the opposite direction at which time the blade 21 in moving causes the blade 20 to move and carries it so that all blades 85 align and fit one above the other. By this means the blades are collapsed for the easy introduction and removal from the mouth of the jar 10 and can be extended after being placed in the jar so as to present the 90 greatest dasher surface possible.

As shown in Fig. 5, the lower section 19 is provided with a notch 26 adjacent the periphery thereof at one corner, while the lug 28 is provided upon the hub 29 thereof. As 95 before noted the blade 21 is provided with the lug 30 which is carried by its hub 31.

Where so desired a spring 33 is mounted

upon the stem 13, this being so arranged as to elevate the dasher during the vertical movement or reciprocation thereof in the churning action.

5. What I claim as new is:

1. A churn dasher including a handle operated stem, a dasher member carried thereby, said dasher member being composed of a plurality of segments one of said segments 10 being fixedly connected to the lower end of the stem and the remainder being mounted for independent rotary movement, coöperative means carried by the segments whereby when either the lower or upper one is moved 15 in an opposite direction to the other, the respective segments are moved in succession into or out of alinement, and coöperative means mounted upon the stem and engaging the upper segment for permitting such action.
2. A churn dasher including a handle operated stem, a tube mounted upon the stem for sliding and rotary movement, a cover carried by said tube, and a dasher member 25 mounted upon the lower end of the stem and including a plurality of segments, the lowermost of said segments being mounted fixedly to the stem and the others being mounted for independent rotary movement, co- 30 operative means carried by the segments whereby when the upper segment is held fixed and the stem is rotated the segments are caused to be moved into alinement or engaged to form a disk.
3. A churn dasher including a handle operated stem, a tube mounted upon the stem for sliding and rotary movement, a cover carried by said tube, a dasher member mounted upon the lower end of the stem and 40 including a plurality of segments the lowermost of said segments being mounted fixedly to the stem and the others being mounted for independent rotary movement, coöperative means carried by the segments whereby 45 when the upper segment is held fixed and the stem is rotated the segments are caused to be moved into alinement or engaged to

form a disk, and coöperative means carried by the upper segment and the tube whereby the upper segment is held stationary 50 while the stem is being rotated.

4. A churn dasher including a handle operated stem, three perforated segmental members mounted upon the lower end of said stem, the lowermost being fixedly connected to stem and the other two being mounted for independent rotary movement upon the stem, coöperative means carried by the segments whereby successive movement is imparted to each due to the rotation of 60 either the stem or the uppermost segment, a sleeve surrounding the stem and fixedly connected to the uppermost disk, a second sleeve mounted for rotary and sliding movement upon the stem, and coöperative means carried by the adjacent ends of the tube and sleeve whereby when the same are in engagement the uppermost disk is held against rotation during the movement of the stem to permit of the extension or collapsing of the 70 segments.

5. A churn dasher including a handle operated stem, three perforated segmental members mounted upon the lower end of said stem, the lowermost being fixedly connected to stem and the other two being mounted for independent rotary movement upon the stem, coöperative means carried by the segments whereby successive movement is imparted to each due to the rotation of 80 either the stem or the uppermost segment, a sleeve surrounding the stem and fixedly connected to the uppermost disk, a second sleeve mounted for rotary and sliding movement upon the stem, coöperative means carried 85 by the adjacent ends of the tube and sleeve whereby when the same are in engagement the uppermost disk is held against rotation during the movement of the stem to permit of the extension or collapsing of the segments, and a closure member carried by said sleeve.

In testimony whereof I affix my signature.
CHAS. W. EBELING.
